H. W. OLIVER,
FOLDING T-SQUARE.

No. 430,809.

Patented June 24, 1890.

UNITED STATES PATENT OFFICE.

HENRY W. OLIVER, OF NEW YORK, N. Y.

FOLDING T-SQUARE.

SPECIFICATION forming part of Letters Patent No. 430,809, dated June 24, 1890.

Application filed October 29, 1889. Serial No. 328,534. (No model.)

To all whom it may concern:

Be it known that I, HENRY W. OLIVER, of the city, county, and State of New York, have invented a new and Improved T-Square, of which the following is a full, clear, and exact description.

The object of the invention is to provide a new and improved T-square adapted to be conveniently folded up for transportation and easily extended and unfolded for use.

The invention consists of a head comprising two arms pivoted to the blade and adapted to be folded thereon or extended in line with each other and at angles to the blade.

15 The invention also consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a plan view of the improvement as folded up. Fig. 2 is a side elevation of 25 the same with parts in section. Fig. 3 is an inverted plan view of the same. Fig. 4 is a plan view of an extension for the blade. Fig. 5 is an end elevation of the same. Fig. 6 is a plan view of the improvement as unfolded, 30 parts being broken out. Fig. 7 is an inverted plan view of the same with the head unfolded and parts broken out. Fig. 8 is a sectional end elevation of the improvement on the line $x-x$ of Fig. 6. Fig. 9 is an end 35 elevation of the improvement folded up and parts in section. Fig. 10 is an inverted plan view of one of the arms of the head. Fig. 11 is a plan view of the turning-plate for one of the heads, and Fig. 12 is a plan view of part 40 of one of the head-arms.

The improved T-square A is provided with a blade B, made in several sections B' B², &c., and of the heads C and D, held near one end of the blade B, at opposite sides of the same. 45 The blade-section B' is provided on its outer end with a metallic binding E, and a similar binding E' is formed on the adjoining end of the section B². A screw E² is formed in the middle of the binding E', as is plainly shown 50 in Fig. 2, and is adapted to screw into a nut E³, formed on the binding E of the blade-section B'. From the screw E² extends a pin

E⁴, adapted to fit into a corresponding aperture E⁵, formed in the blade-section B'. The pin E⁴ is slightly less in diameter than the 55 screw E², so that when the two blade-sections are to be fastened together the pin E⁴ is passed through the nut E³ into the opening E⁵, and then the screw E² is screwed into the nut E³ until the edges of the bindings E 60 and E' abut against each other, as is plainly shown in Fig. 3.

In order to lock the two blade-sections B' and B² in place, I provide sliding bolts E⁶, held to slide in suitable recesses in the blade-section B', and adapted to engage corresponding recesses E⁷, formed in the binding E' of the blade-section B². Each of the sliding bolts E⁶ is provided with a knob E⁸, projecting through a slot E⁹, formed in the top 70 of the blade-section B', so that the operator can conveniently engage said knob E⁸ with a finger-nail, in order to slide the bolt E⁶ forward or backward to engage or disengage the recesses E⁷ in the binding E'. It is understood that any desired number of such blade-sections B² may be joined one on the other by providing the outer end of the blade-section B² with a binding E and sliding bolts E⁶, such as are found on the outer end of the 80 blade-section B'.

The head C is provided with two arms C' and C², each provided with a straight front edge C³ and a parallel back edge C⁴. The arms C' and C² are mounted to swing on fixed 85 pivots F', formed on a plate F, secured on the rear end of the blade-section B'. In order to prevent the arms C' and C² from becoming detached from the pivots F', a transverse bar G is placed across the adjoining ends of the 90 arms C' and C², and secured by screws G' to the pivots F', as is plainly shown in Figs. 1 and 8. The back edges C⁴ of the arms C' and C² are adapted to abut against lugs F², formed on the plate F, and each provided 95 with a shoulder F³, adapted to be engaged by a corresponding shoulder C⁵, formed on the arms C' and C². When the latter are in an innermost position, as shown in Fig. 1, the shoulders C⁵ and F³ abut against each other, 100 thus preventing the respective arms C' or C² from moving too far inward on the blade B. When the two arms C' and C² are extended, as shown in Fig. 6, the front edges C³ of the

two arms are in line with each other and at right angles to the blade B. The arms C' and C² are prevented from swinging too far outward by the back edges C⁴, abutting against the lugs F².

In order to prevent the front edges C³ from getting out of alignment when extended, I provide a screw C⁶ on each of the arms C' and C², said screw screwing in the back edge C⁴ and being adapted to abut with its head against the respective lug F². By adjusting the screw C⁶ the front edges C³ of the two arms C' and C² can always be kept in alignment when extended. Near each outer end of the arms C' and C² is formed a recess C⁷ for conveniently moving the arms C' and C² into an extended or folded position. When the two arms C' and C² are extended, both of their front edges C³ are at right angles to the blade B, and then the T-square can be used in the usual manner.

In order to draw inclined lines along the blade B, the head D is provided, which also has two pivoted arms D' and D², which, when extended, have their front edges D³ in line with each other; but said arms can be moved to any desired angle to the blade B, as illustrated in Fig. 7. Each of the arms D' and D² is provided on its inner end with a metallic plate D⁴, provided with a circular offset D⁵, (see Figs. 7 and 12,) fitting into a corresponding aperture I', formed in a plate I, mounted to turn on a screw H, which also serves to hold the plate F, previously mentioned, onto the blade B. The back edge of the metallic plate D⁴ is adapted to abut against a shoulder I², formed on the plate I, so that when the arms D' and D² are extended and the side plates D⁴ abut against the shoulders I², then the front edges D³ of the two arms D' and D² are in line with each other. As the arms D' and D² are held on the plate I mounted to turn, their front aligned edges D³ can be moved into any desired angle with the blade B.

From the movable plate I extends a segmental plate I³, provided with a graduation I⁴, indicating degrees and subdivisions of the same, and on which indicates a pointer J, secured on a plate J', held in bearings F⁴, formed on the plate F, previously mentioned. From the under side of the plate J' extends a bolt J², which passes through the plate F, and on the outer end of which screws a nut K against the said plate F, so as to move the pointer J with more or less force in contact with the segmental plate I³, thereby holding the latter and its plate I in any desired position into which it may have been moved. The pointer J at the same time indicates the degree to which the front edges D³ of the arms D' and D² are set relative to the blade B.

The metallic plate D⁴ on each of the arms D' and D² is so formed relatively to the apertured part of the plate I that the inward-swinging motion of the arms is limited, and the two edges D³ cannot be brought in contact with each other, as is plainly shown in Fig. 3, and their outward movement is de-

fined, as shown in Fig. 7. A screw D⁷, passing through the arms D' D² and the offset D⁵ of the respective plates D⁴, holds the said parts 70 in place.

It will be seen that the two heads C and D, arranged on opposite sides of the blade B, operate independently of each other, the head C being used for ordinary work, while the head D is used for drawing angular lines on the drawing-board. It will further be seen that when the head D is extended and set to a desired angle the head is locked in place by screwing up the nut K, so that the pointer 80 J locks the graduated segmental plate I³ in place, thus preventing displacement of the head when in this angular position.

Having thus fully described my invention, I claim as new and desire to secure by Letters 85 Patent—

1. In a T-square, a head comprising two arms pivoted to the blade and adapted to be folded thereon or extended in line with each other and at angles to the blade, substantially as shown and described.

2. In a T-square, the combination, with a blade, of a head comprising two arms pivoted to the said blade and adapted to be folded thereon or extended in line with each other 95 and at angles to the said blade, substantially as shown and described.

3. In a T-square, the combination, with a blade, of a head held on the said blade and comprising two arms and a plate on which 100 said arms are pivoted, and which itself is pivoted on the said blade, substantially as shown and described.

4. In a T-square, the combination, with a blade, of a head held on the said blade and comprising two arms, a plate on which said arms are pivoted, and which itself is pivoted on the said blade, and means, substantially as described, for locking the said plate in place, as set forth.

5. In a T-square, the combination, with a blade, of a head held on the said blade and comprising two arms, a plate on which the said arms are pivoted, and which itself is pivoted on the said blade, a graduated segment 115 formed on the said plate, and a fixed pointer held on the said blade and indicating on the said graduation, substantially as shown and described.

6. In a T-square, the combination, with a blade, of a head held on the said blade and comprising two arms, a plate on which the said arms are pivoted, and which itself is pivoted on the said blade, a graduated segment formed on the said plate, a fixed pointer held on the said blade and indicating on the said graduation, and a nut for locking the said pointer onto the said graduated segment, substantially as shown and described.

7. In a T-square, the combination, with a blade, of a head comprising two arms pivoted to the said blade and lugs held on the said blade and adapted to be engaged by the said arms, substantially as shown and described.

8. In a T-square, the combination, with a blade, of a head comprising two arms pivoted to the said blade, and each provided with a shoulder, and lugs held on the said blade and adapted to be engaged by the said arms, and each of said lugs being provided with a shoulder to engage the shoulder of the corresponding arm, substantially as shown and described.

9. In a T-square, an extension-blade comprising a series of blade-sections, of which one is provided with a screw engaging the other, and locking-bolts for locking the two sections in place, substantially as shown and described.

10. In a T-square, the combination, with a blade-section provided with a metal binding in which is formed a nut, of a second blade-section provided in one end with a screw adapted to engage the said nut of the other blade-section, substantially as shown and described.

11. In a T-square, the combination, with a blade-section provided with a metal binding in which is formed a nut, of a second blade-

section provided in one end with a screw adapted to engage the said nut of the other 25 blade-section and a pin formed on the said screw and adapted to engage a corresponding recess in the other blade-section, substantially as shown and described.

12. In a T-square, the combination, with a 30 blade-section provided with a metal binding in which is formed a nut, of a second blade-section provided in its middle at one end with a screw adapted to engage the said nut of the other blade-section, a pin formed on 35 the said screw and adapted to engage a corresponding recess in the other blade-section, and locking-bolts held in one of the blade-sections and adapted to engage the other blade-section, substantially as shown and de- 40 scribed.
